PROCESS FOR PRODUCING MOTOR FUEL

Robert F. Marschner, Chicago, Ill., assignor to
 Standard Oil Company, Chicago, Ill., a corpora-
 tion of Indiana

Application October 23, 1939, Serial No. 300,734

2 Claims. (Cl. 260—683.6)

This invention relates to an improved process for producing fuels for internal combustion engines. More particularly, it relates to an improved process for producing aviation gasoline. Still more particularly, it relates to a process which produces both improved aviation gasoline and improved motor fuel.

In the manufacture of 100 octane number and higher aviation fuels by polymerizing the C₄ cut from cracking and reforming still gases and hydrogenating the polymer, it has been found necessary to blend the isoctane and tetraethyl lead with appreciable quantities of lighter hydrocarbons in order to meet the specifications of aviation fuel. This may be accomplished by blending the isoctane with a straight-run light naphtha fraction. While this results in the production of a fuel of the desired specifications, it would be preferable to employ a material for blending with the octane which would reduce its octane number to a lesser extent.

It is, therefore, an object of this invention to provide an improved process for producing aviation fuel which involves polymerization of C₄ hydrocarbons and hydrogenation of the polymers. A further object is to provide such a process in which the resulting fuel not only meets the specifications for aviation fuel but, in addition, has a higher octane number than such fuels have heretofore had.

Another object of this invention is to produce an improved blended aviation fuel containing isoctane. Still another object is to provide a process which produces both isoctane and a hydrocarbon fraction which, when blended with the isoctane, gives an improved aviation fuel.

These objects may be accomplished in connection with the polymerization of four carbon atom olefin hydrocarbons (hereinafter called "C₄ olefins") and hydrogenation of the polymer to form isoctane by separating from a hydrocarbon oil which has been subjected to treatment adapted to decrease the average molecular weight of the constituents thereof, such as cracking or reforming treatment, a fraction containing substantial amounts of five carbon atom olefin hydrocarbons (hereinafter called "C₅ olefins"), which fraction is largely free of hydrocarbons lighter than C₄, and in which fraction C₅ hydrocarbons boiling below about 90° F. at atmospheric pressure predominate over those of higher boiling point to a substantially greater extent than in the aforesaid treated hydrocarbon oil and then treating the C₅ hydrocarbons included in said fraction to decrease the concentration of C₅ ole-

fins therein. The fraction should contain at least from about 2% of C₅ hydrocarbons up to a maximum of 100% and preferably from about 8% to about 15%.

5 The desired C₅ hydrocarbons may be obtained in satisfactory concentration by taking a fraction which distills up to about 90° F. at 1 atmosphere from a cracked or reformed hydrocarbon product from which hydrocarbons lighter than C₄ have been separated. This fraction may or may not include the C₄ hydrocarbons as desired. The invention, moreover, is not limited to the above described source for the C₅ hydrocarbon fraction but includes fractions from other sources which 10 have the same composition as the fraction described above. It is preferred, however, that the fraction be obtained from the same source from which the C₄ hydrocarbons which are to be polymerized to isoctane are obtained. An advantageous feature of these C₅ hydrocarbon containing fractions is that iso C₅ hydrocarbons are a predominant constituent. On the other hand, the percentage of olefins is higher than is permitted in hydrocarbons used for blending with isoctane 15 if the resulting aviation fuel is to meet present specifications, so that it is necessary to subject the C₅ hydrocarbons to a further treatment as disclosed above in which at least a portion of the C₅ olefins is eliminated. This may be accomplished, for example, by hydrogenating the C₅ olefins to pentanes.

20 A convenient and preferred method for affecting this hydrogenation is to send the C₅ hydrocarbons into a hydrogenator along with the polymerized C₄ hydrocarbons so that both are hydrogenated in one operation although the invention is not limited to this feature. If the desired C₅ hydrocarbons have been taken as a separate cut they may be added to the polymers passing from 25 the polymerizer to the hydrogenator. Where the C₅ hydrocarbons are taken off in the same cut with the C₄ hydrocarbons and the pentenes are to be eliminated by hydrogenation the C₅ hydrocarbons are separated from the C₄ hydrocarbons 30 before the latter are sent to the polymerizer and are then added to the polymers passing to the hydrogenator as were the C₅ hydrocarbons taken as a separate cut originally.

25 By taking a cut of C₅ hydrocarbons not above about 90° F. or equivalent temperatures, the fraction obtained predominates in iso C₅ hydrocarbons as pointed out. Accordingly, it will have a much higher octane number than would a straight-run light naphtha fraction, for example. 35 Thus, when it is used in place of light naphtha

to produce aviation gasoline with iso-octane, the resulting blend will have a substantially higher knock-rating than when light naphtha from crude is used. Moreover, this will be true after either hydrogenation or polymerization or both because of the predominance of iso C_5 hydrocarbons. In addition when a substantial portion of the C_5 hydrocarbons are derived from a hydrocarbon oil which has been catalytically cracked the iso C_5 olefins will predominate to a greater than average extent so that the predominating product of hydrogenation is an isopentane and thus the octane number is not materially reduced by this treatment as would be the case were a larger quantity of normal pentenes present in the cut.

Another way of eliminating the C_5 olefins is to subject them to conditions by which they are caused to polymerize to hydrocarbons of higher molecular weight. Thus the cut taken as disclosed above which contains both the C_4 hydrocarbons from which iso-octane is to be formed and the desired C_5 hydrocarbons may be sent directly to the polymerizer without separating the C_5 hydrocarbons whereby both the C_4 and C_5 hydrocarbons are polymerized or co-polymerized, but while this method is preferred the invention is not limited to it as regards polymerization of the C_5 fraction. This preferred polymerization is a "selective" polymerization and results in the production of both octenes and nonenes as well as some higher olefins. By "selective polymerization" is meant a catalytic polymerization under conditions to produce highly branched olefins which conditions are usually at a selected temperature in the range of 300° F. to 600° F., preferably 300° F. to 400° F., and at a pressure sufficiently high to maintain the major portion of the reactants in the liquid or dense phase. The unreacted C_5 hydrocarbons are then preferably passed to a hydrogenator along with the octenes whereby any pentenes present are converted to pentanes although they may be hydrogenated separately from the octenes or if the concentration of pentenes is sufficiently low so that such a quantity of pentenes will not be undesirable in the resulting aviation gasoline, the C_5 hydrocarbons may be separated from the other materials passing out of the polymerization zone and sent directly for blending with the iso-octane obtained from the hydrogenation step to form the desired aviation fuel.

If all the hydrocarbons higher than C_5 which are in the effluent from the polymerizer are sent to the hydrogenator, the iso C_6+ portion of the product having a slightly lower octane number than the iso-octanes makes the manufacture of 100+ octane number fuels by addition of lead more difficult. Moreover, the C_6+ hydrocarbons raise the 50% boiling point above specifications. This disadvantage can, of course, be overcome by fractionating out the C_6+ hydrocarbons, which fractionation is readily carried out. To make these expensive paraffins and then, in effect, waste them by dumping them into relatively cheap regular motor fuels is, however, very inefficient.

It is known from road tests that a motor fuel with a high sensitivity in the heavy ends is very desirable. By "high sensitivity" as used herein, is meant high sensitivity with respect to motor octane number-research octane number relationship. Thus a highly sensitive material is one which shows a large difference in octane number depending upon whether the octane number is

determined by the motor method or by the research method. Thermally reformed naphtha in particular suffers in the respect in question because its heavy ends being largely unreformed, 5 heavy virgin naphthas show a low sensitivity as well as a low octane number. If the C_6+ hydrocarbons present in the products obtained from the polymerizer are separated a fraction is obtained which, because of its substantially 100% olefin content, is a highly sensitive fuel. Moreover, in concentrations below 25% these 83 to 87 octane number olefins may show blending octane numbers far above 100, depending upon the character of the base stock.

A further object of this invention is then to produce a motor fuel with high sensitivity in the heavy ends. A still further object is to provide a process in which hydrocarbons which are undesirable by-products from the manufacture of 20 aviation fuel are utilized to advantage in the production of high sensitivity motor fuel. Another object is to provide a process in which both improved aviation gasoline and improved motor fuel are produced. Another object is to provide a process in which hydrocarbons produced in the manufacture of aviation gasoline and which would otherwise be wasted are utilized to improve 25 motor fuel. Another object is to provide a process in which a narrow cut of C_5 hydrocarbons is treated in such a way that the whole content of 30 the cut is used to advantage in the production of fuel for internal combustion engines. Another object is to provide a process in which a narrow cut of C_5 hydrocarbons is so treated that its use 35 results in the production of both improved aviation gasoline and improved motor fuel. Other objects will appear hereinafter.

These further objects are accomplished by separating the C_6+ olefins from the products obtained by selectively polymerizing a mixture of C_4 and the narrow cut of C_5 hydrocarbons repeatedly referred to above and then blending the C_6+ olefins into a motor fuel, such as cracked naphtha or particularly a thermally reformed 40 naphtha motor fuel in the manner described below in place of a portion of the heavy naphtha which would otherwise be present therein. As described above, the C_5 hydrocarbons remaining in the polymerization products may be sent to the 45 hydrogenation step along with the other hydrocarbons lighter than C_6 or they may be separated prior to hydrogenation if they are not too unsaturated to be used in blending with iso-octane to make aviation fuel.

In order that the invention may be better understood, reference is made to the attached drawing which forms a part of the specification and which is a schematic illustration of an apparatus suitable for carrying out the invention. It should be understood, however, that the invention is not limited to this particular apparatus which is shown for purposes of illustration only and not for the purpose of limiting the scope of the invention.

Referring to the drawing, hydrocarbon oil boiling above about 250° F., for example, naphtha having a boiling range from about 250° F. to about 400° F. or gas oil having a boiling range from about 380° F. to about 750° F. is introduced 65 through line 10 containing valves 11 and 12 into heater 13 wherein it is either cracked or reformed or else heated to a suitable temperature for introduction into catalyst chamber 16 through lines 14 and 15 wherein it is either catalytically cracked or reformed. It will be observed that if

cracking or reforming is to be accomplished in heater 13, valve 18 in line 15 and valve 20 in line 17 will be closed and valve 19 will be open. If, on the other hand, the oil is to be catalytically cracked or reformed, valve 19 is closed and valves 18 and 20 are open.

The cracked or reformed oil then passes either through line 14 into line 17 or else through lines 14 and 15 and catalyst chamber 16 into line 17 and through line 17 into fractionator 21. From fractionator 21 light naphtha and lighter products are taken overhead through line 23 and heavy naphtha and gas oil are taken off respectively through lines 25 and 26, any tar formed being drawn off the bottom through line 22. The gas oil drawn off through line 26 is recycled through line 69 and valve 71 to line 10 and thence to heater 13. If the fresh feed entering through line 10 is naphtha which is being reformed either thermally or catalytically, fractionator 21 may be operated so that everything heavier than light naphtha except tar is taken off as heavy naphtha through line 25. In this case, valve 32 in line 26 will be closed.

Whether or not gas oil is being taken off through line 26 it may be desirable to recycle part or all of the heavy naphtha taken off through line 25. The quantity of heavy naphtha recycled may be controlled by valve 70 in line 69 and valve 83 in line 25 or if gas oil is being taken off the heavy naphtha cut may be taken at a narrower temperature range so that the heavy ends of the naphtha which are to be recycled are taken off in the gas oil recycle cut. When the process described herein is operated in the preferred manner to produce both aviation gasoline and high sensitivity motor fuel, the quantity of heavy naphtha which is recycled may vary widely. It will be determined not only by the desired boiling range of the motor fuel, the desired octane number and the desired sensitivity but also by the quantity of C₉+ olefins being produced. In general, it may be said that at least sufficient heavy naphtha should be recycled to prevent the 50% boiling point from being raised above the desired figure by the addition of the C₉+ olefin polymers. Where all of the heavy naphtha is being cut as a single cut this may involve recycling as much as 40% of it or more, although generally 20% or less, preferably about 10%-15%, is all that need be sent back for further treatment. Where a gas oil cut is being taken it is preferable to include the heavy ends of the heavy naphtha in the gas oil recycle cut by taking the heavy naphtha cut over a narrower temperature range as outlined above. Thus, the upper temperature limit of the heavy naphtha cut which is usually about 400° F. may be lowered to 320° F. or even lower although it will usually be satisfactory to continue this heavy naphtha cut up to 340° F. and preferably to 375-380° F. allowing only that portion coming over above these temperatures to pass out in the gas oil recycle cut. Heavy naphtha to be used in a gasoline blend is drawn off through line 25 and valve 83.

When cracked or reformed hydrocarbons are available from other sources they may be introduced into the system through line 72 and valve 73 from which they are passed by line 17 into the fractionator 21 and thereafter cut as described above. Such cracked products from line 72 may constitute the sole feed to the system or may be in addition to cracked products coming from heater 13 or catalyst chamber 16.

The light naphtha and lighter products taken

overhead through line 23 pass through condenser 27 and line 28 into separator 29. Uncondensable gases such as hydrogen and methane are taken off the top of separator 29 through line 30. The liquid in separator 29 is drawn off the bottom through pump 74 and line 31 a portion being returned through line 24 to the top of fractionator 21 as reflux and the remainder passing through line 32 into stabilizer 33 having bottom heating means.

Stabilizer 33 is operated so that C₃ and lighter hydrocarbons are drawn off as gases from the top through line 34. Liquids are drawn off the bottom of stabilizer 33 and pass through line 35 and valve 84 into superfractionator 36 having bottom heating means. This fractionator is operated so that the cut taken off the top through line 38 is distilled off up to a temperature of about 90° F. or below at atmospheric pressure; however, the stabilizer itself will preferably be operated under pressure. This overhead cut will then consist of the C₄ hydrocarbons and the desired C₅ hydrocarbons. Higher boiling material is withdrawn from the bottom of superfractionator 36 as light naphtha. This light naphtha passes through valve 98 and lines 37 and 58 into line 25 where it is blended with heavy naphtha and other hydrocarbons to be described later to form motor fuel. If desired, the supply of C₄ and C₅ hydrocarbons passing to superfractionator 36 may be augmented by supplying C₄ and C₅ hydrocarbons from other sources, particularly from catalytic cracking, with or without heavier hydrocarbons boiling within the boiling range of light naphtha through line 39 and valve 40 or, if an adequate supply of such a feed is available it may constitute the sole feed to superfractionator 36 in which case valve 84 will be closed.

The C₄ and C₅ hydrocarbons taken overhead from superfractionator 36 through line 38 may be passed through valve 42 and line 41 into fractionator 46 by closing valve 43 and opening valves 42 and 45 or they may be by-passed around fractionator 46 by closing valves 42 and 45 and opening valve 43. When the C₄ and C₅ hydrocarbons are passed through fractionator 46 a separation between the C₄ and C₅ hydrocarbons is effected therein, the C₄ hydrocarbons being drawn off the top through line 44 and valve 45 and the C₅ hydrocarbons being drawn off the bottom through line 47.

If fractionator 46 has not been used, the C₄ and C₅ hydrocarbons pass through line 38 into polymerizer 48 wherein the unsaturated hydrocarbons are selectively polymerized. The polymers and unreacted materials leave polymerizer 48 through line 49 and pass into debutanizer 50 having a reboiler. Butanes leave debutanizer 50 through valve 51 and line 54 from which they are introduced into line 58 and thence into line 25 where they are blended with the light and heavy naphtha separated as hereinbefore described to form motor fuel. If only the C₄ hydrocarbons have been fed to the polymerizer 48 the products leaving the bottom of debutanizer 50 through line 52 are caused to pass through line 52 into hydrogenator 62 by opening valves 55 and 56 and closing valves 54 and 60. The C₅ hydrocarbons separated in fractionator 46 are blended with the polymer products in line 52 by opening valves 67 and 99 and allowing them to enter line 52 and pass with the polymers into hydrogenator 62. Hydrogen is introduced into hydrogenator 62 through line 61 and unreacted hydrogen and the hydrogenated mixture of C₅ hydrocarbons and

polymers are drawn from hydrogenator 63 through line 63. This mixture passes through line 63 into separator 65 wherein excess hydrogen is separated and drawn off through line 64 and valve 101. The liquids in separator 65 are then drawn off through line 66 and valve 100 as finished aviation gasoline.

When both aviation gasoline and motor fuel of high sensitivity are being made instead of separating the C₅ hydrocarbons from the C₄ hydrocarbons in fractionator 46 the mixture leaving superfractionator 36 passes through line 38 and valve 43 directly into polymerizer 48, valves 42 and 45 in this instance being closed. After being selectively polymerized in polymerizer 48 the mixture passes through line 49 into debutanizer 50 as described above when only the C₄'s were passed to the polymerizer. Debutanizer 50 is also operated in the way which has already been described so that only the C₄ hydrocarbons are taken out through line 51. The remainder of the charge leaves debutanizer 50 through line 52 as before but this time valves 55 and 56 are closed and valves 54 and 60 are open so that the materials pass through line 52 into line 53 and through valve 54 into fractionator 57. Fractionator 57 is so operated that the C₅ and higher olefins are taken off as a bottom product through line 58 and valve 68 and thence into line 25 so that the motor fuel drawn off through line 25 is a blend of light naphtha, heavy naphtha, butanes and the C₅ and higher olefins derived from fractionator 57. In making such a gasoline which has a very high sensitivity a portion of the heavy naphtha withdrawn from fractionator 21 through line 25 is recycled through line 69 and line 10 to heater 13. This portion of heavy naphtha recycled is adjusted so that it is about equal to the quantity of C₅ and higher olefins withdrawn from fractionator 57 through line 58. A portion of the heavy naphtha in the gasoline withdrawn through line 25 is thus replaced by an equivalent quantity of the C₅ and higher olefins.

The products leaving the top of fractionator 57 through line 59 consist mainly of C₅ and C₆ hydrocarbons. They may be passed through valve 60 to line 52 and into hydrogenator 62, hydrogen being passed through line 61 into hydrogenator 62 as before. In operating in this manner any C₅ olefins not polymerized in polymerizer 48 are hydrogenated in hydrogenator 62 along with the isooctane so that after the products of hydrogenation are separated from excess hydrogen in separator 65 a finished aviation gasoline is drawn off through line 66.

If the hydrocarbons leaving fractionator 57 through line 59 are sufficiently low in C₅ olefins so that the quantity will not be objectionable in aviation gasoline it is unnecessary to hydrogenate these C₅ hydrocarbons and the quantity of material passing to hydrogenator 62 can thus be decreased by closing valve 60 and opening valve 75 so that the overhead from fractionator 57 passes through line 78 into depentanizer 77 having a reboiler. The C₅ hydrocarbons are drawn off the top of depentanizer 77 through line 79, condenser 102, and valve 19 where they are blended with the gasoline withdrawn from separator 65 through line 66 to give the finished aviation gasoline withdrawn from line 66. The hydrocarbons higher than C₅ leave the depentanizer 77 through line 80 and pass through valve 81 into line 52 and thence into hydrogenator 62 and separator 65 wherein excess hydrogen

is separated as before and from which they are withdrawn through line 69 wherein they are blended with the C₅ hydrocarbons from line 78 as pointed out above making finished aviation gasoline of the desired characteristics.

It will thus be seen that this process may be operated in any one of three ways each of which has, however, the common characteristic that C₅ hydrocarbons boiling up to about 90° F. at atmospheric pressure are separated from other C₅ and higher hydrocarbons after which these lower boiling C₅ hydrocarbons are treated to decrease the concentration of C₅ olefins therein and then withdrawn from the system as a constituent of a finished aviation gasoline which has not only a high knock rating but which, in addition, has improved boiling characteristics.

It is not always convenient or practical to produce the various components of either the motor fuel or the aviation gasoline in the exact proportions desired for blending so that it is usually necessary to store one or more of these cuts or products. For this reason valved lines are provided for drawing off and sending to storage (not shown) for use at other times or for other uses, the C₄'s from line 51, the C₅'s from either line 47 or line 78, the light naphtha from line 37, the heavy naphtha from line 25, and the C₅ and higher olefins from line 58. These lines with their accompanying valves, are, respectively, line 89 and valve 90, line 95 and valve 96, line 83 and valve 94, line 87 and valve 88, line 85 and valve 86, and line 91 and valve 92. No additional means for drawing off hydrogenated materials separately from C₅'s entering line 66 through line 78 is shown since line 66 itself can be used for this purpose when valve 78 is closed.

A preferred method of operation involves introducing naphtha through line 10, and either 40 thermally reforming or thermally cracking it in heater 13, then fractionating the cracked or reformed materials in fractionator 21 so that light naphtha and lighter materials are drawn off the top, so that heavy naphtha is drawn off through line 25, and so that the material heavier than heavy naphtha such as tar passes out through line 22. A portion of the heavy naphtha roughly corresponding in quantity to the quantity of C₅ and higher olefins leaving fractionator 57 through line 58 is recycled through line 68. Separator 29, stabilizer 33, and superfractionator 36 are all operated in the manner already described above but the feed through line 35 to superfractionator 36 is supplemented by introducing through line 29 and valve 40, a fraction of a mixture of hydrocarbons obtained by catalytically cracking naphtha, gas oil or similar hydrocarbon oil and fractionating to remove heavy naphtha and heavier hydrocarbons as well as hydrocarbons lighter than C₄. Such a fraction will be high in olefin content as well as in content of iso C₄ and iso C₅ olefins and paraffins. The mixture of C₄ and C₅ hydrocarbons leaving superfractionator 36 through line 38 is, in the preferred process, by-passed around fractionator 46 by closing valves 45 and 67 and is sent directly to polymerizer 48. After being subjected to selective polymerization therein the hydrocarbons are debutanized in debutanizer 50 and then sent to fractionator 57 by having valves 55 and 56 closed and valve 54 open. In fractionator 57 the C₅ and higher olefins are drawn off the bottom and are sent back to replace the heavy naphtha recycled in forming the blended gasoline of high sensitivity which is with-

drawn through line 25. With valves 79, 81 and 75 closed and valve 60 open the overhead from fractionator 57 is then passed through line 52 into hydrogenator 62 and then into separator 65 and a finished aviation gasoline is withdrawn through line 66. Depending upon the relative quantities of each, the various constituents of both the motor fuel and the aviation gasoline may, if desired, be sent in part or wholly to storage prior to blending to form the finished products.

The conditions of operation to be used in connection with the various towers, furnaces, etc., shown on the accompanying flow sheet and described above are in large part familiar to those skilled in the art since they are conventional and, therefore, detailed conditions of operation need not in every instance be specified. The above description of the purpose of these various pieces of equipment, is, in general, sufficient to enable anyone skilled in the art to practice the process of the invention.

Accordingly the invention is not limited as to conditions of operation so long as the conditions are such as to effect in the towers, furnaces, etc., the operations which are fully described above. Certain conditions are, however, preferred. Thus when a hydrocarbon oil is being treated thermally in heater 13 it is preferable that the temperature be in the range from about 900° F. to about 1025° F. for example 975° F. and that the pressure be about atmospheric or above up to about 1000 lbs., for example 200 lbs. Under these conditions a soaking time sufficient to give about 10% to about 50% of gasoline per pass is preferred. For catalytic cracking or reforming, temperatures in the range from about 750° F., to about 950° F., for example 875° F., rates of feed such that about 0.1 to about 5 volumes of liquid oil feed are passed per hour per volume of catalyst space, for example 1 volume, pressures from about atmospheric to about 50 lbs., for example 10 lbs., and catalyst holding times of about 5 minutes to about 10 hours, for example, 30 minutes, are preferred. Preferred cracking and reforming catalysts include absorbent earths, such as natural or synthetic clays, as well as active catalysts, such as alumina, thoria, or zirconia hydrolytically absorbed or otherwise mounted on a siliceous support. Phosphoric acid on kieselguhr or any other known cracking or reforming catalyst may, however, be used, if desired.

As has already been indicated the polymerization described above is preferably "selective." In the definition of "selective polymerization" given in connection with the first use of the term herein, it is stated among other things that the polymerization is catalytic and that it is under sufficient pressure to maintain the reactants in the liquid or dense phase. Preferred catalysts for this polymerization include catalysts of the phosphoric acid on kieselguhr type, as well as those of the copper pyrophosphate type or catalysts equivalent to these types. In stating that the reactants should be under sufficient pressure to maintain them in the liquid or dense phase, it is meant that the pressure should be at least high enough so that the reactants are in that portion of the dense phase region which is above the extrapolated vapor pressure curve for the charge. Moreover, although "selective polymerization" is preferred, it is within the scope of the invention to employ other polymerization procedures which lead to the production of high octane number

fuels, such as low temperature processes using liquid catalysts, for example, sulfuric acid or sulfuric acid-phosphoric acid mixtures. In such processes the flow rate will depend on the activity of the catalyst and should be such that preferably from about 80% to about 100% of the isobutylene in the charge is converted to higher boiling materials. In this connection it may be mentioned that it is, of course, within the scope of the invention to recycle unreacted C₄ olefins to the polymerization step or to polymerize in more than one stage, if desired, whether the polymerization be according to preferred methods or not. Since such variations are well within the knowledge of the art it is not believed to be necessary to illustrate them, however.

For the hydrogenation step, one of two commercially recognized types of procedure is preferred. These types are the high pressure process, using specially composed 6th group catalysts, preferably a catalyst comprising molybdenum, and the low pressure process using nickel. Preferred conditions for the high pressure process are temperatures in the range from about 550° F. to about 850° F., for example 725° F., pressures in the range from about 250 lbs. to about 5000 lbs., for example 450 lbs., hydrogen to olefin molar ratios from about 2 to about 25, for example 8 and rates of flow of about 0.1 to about 5 volumes of liquid hydrocarbon feed/volume of catalyst space/hour, for example 0.6 volume hydrocarbon/volume catalyst space/hour.

For the low pressure process the preferred operating conditions involve temperatures in the range from about 200° F. to about 500° F., for example 425° F., pressures from about 10 lbs. to about 150 lbs., for example 35 lbs., excess of hydrogen over the theoretical of from about 3% to about 100%, for example 10%, and rates of flow of about 1 to about 15 volumes of liquid hydrocarbon feed/volume of catalyst space/hour, for example, 4 volumes hydrocarbon-volume of catalyst space/hour.

By way of further facilitating a complete understanding of the present invention, the following example is included. It should be understood that this example is included for illustration only and, therefore, it is not intended to be construed as limiting the scope of the invention.

Example.—Gas oil is about 30% thermally cracked at about 975° F. under a pressure of about 250 pounds per square inch and the product is separated into fixed gas, wet gas, light naphtha (250° F.—E. P.), heavy naphtha (380° F.—E. P.), cycle stock and tar. It will be noted that the heavy ends of the naphtha are thus included in the cycle stock. The combined wet gas and light naphtha is stabilized C₃-free and about 25 volumes percent of a similarly stabilized fraction from catalytic cracking is added. This mixture is then superfractionated to about 90° F. at one atmosphere to give a mixture overhead of about 79% C₄ hydrocarbons which are about 48% unsaturated and contain about 22% isobutylene, the rest of the mixture (about 21%) being C₅ hydrocarbons, which are also about 48% unsaturated and contain a proportion of branched olefins approximating that in the C₄ hydrocarbons, the non-olefin material including relatively small amounts of n-pentane. This overhead mixture of C₄ and C₅ hydrocarbons is then passed over a phosphoric acid on kieselguhr catalyst at a temperature of about 345° F. under a pressure of about 985 pounds per square inch gage, at a rate of about 10 volumes of liquid hydrocarbons

per volume of catalyst per hour by which about 95% of the branched C₄ and C₅ olefins and about 60% of the total C₄ and C₅ olefins are polymerized to liquids. Upon fractionation of the product about 55% passes overhead below about 46° F. This overhead which consists almost entirely of C₄ hydrocarbons is blended in motor fuel or stored for use for this or other purposes. The portion (about 45%) of the product remaining after removal of the C₄'s is then further fractionated. In this fractionation an overhead fraction is taken up to about 255° F. and consists of about 42% C₅ (containing 19% olefins) and about 58% dibutylenes. It amounts to about 30% of the total effluent from the polymerization. The other 15%, which remains as bottoms in the latter fractionation, consists of C₆ and higher (1/3 C₁₂'s and 2/3 C₆-C₁₀) hydrocarbons. It is then blended in a motor fuel or stored for use for this purpose. The overhead fraction of C₅'s and dibutylenes is then non-destructively hydrogenated at a temperature of about 425° F. over a nickel catalyst under a pressure of about 35 pounds using an excess of hydrogen over the theoretical of about 10%. The product is an aviation gasoline with an octane number of about 90-92 and a vapor pressure at 100° F. of more than 6 pounds. To obtain a product of similar volatility by blending a 67 O. N. light straight run naphtha with the commercial isooctane lowers the octane number to about 85. Moreover, the lead response of the 90-92 O. N. product is actually slightly higher than that of the iso-octane-light naphtha blend. When the heavy naphtha fraction separated as described above having a motor octane number of about 61 is blended with the C₆-C₁₂+ bottoms described above which have a motor octane number of about 62 and replace the portion of the heavy naphtha included in the gas oil fraction and recycled, the motor octane number of the heavy blend is increased to about 68. This heavy blend and the light naphtha are combined with sufficient of the C₄'s separated above to produce a balanced motor fuel which shows good sensitivity throughout its boiling range as shown by the following table:

Fraction	Sensitivity
Below 250° F.	5.5
Above 250° F. (before adding C ₆ +bottoms)	6.9
Above 250° F. (after adding C ₆ +bottoms)	3.2

The advantages of the present invention will be apparent from the above description. In the production of aviation gasoline by polymerization and hydrogenation of C₄ hydrocarbons a method is provided for overcoming the difficulty heretofore encountered in obtaining gasoline of the desired boiling characteristics without unduly reducing the octane number at the same time.

This is accomplished without the necessity for any additional equipment over that employed to polymerize and hydrogenate the C₄ hydrocarbons. Moreover, the presence of the C₅ hydrocarbons during selective polymerization is, itself, advantageous since it helps to maintain the desired dense phase. An even more outstanding advantage of the process is that it is possible to produce along with the improved aviation gasoline an improved motor fuel from reformed naphtha which has a desired high sensitivity in the heavy ends. Another advantage of the process when operated in accordance with the preferred method is that the C₅ olefins are eliminated largely by polymerization thereby decreasing the charge to the more expensive hydrogenation operation.

It is apparent that many widely different embodiments of this invention may be made without departing from the spirit and scope thereof and, therefore, it is not intended to be limited except as indicated in the appended claims.

I claim:

1. The process which comprises thermally cracking gas oil, fractionating the resulting mixtures into a tar fraction, a recycle fraction including the heavy ends of heavy naphtha, a discard fraction lighter than C₄, a fraction including the rest of the heavy naphtha, and a light naphtha fraction including the C₄ and C₅ hydrocarbons, adding to said light naphtha fraction a substantial quantity of a similar fraction from catalytic cracking, fractionating the resulting mixture into a bottom light naphtha fraction and an overhead fraction containing the C₄ hydrocarbons and such of the C₅ hydrocarbons as are included by taking the cut up to about 90° F. at atmospheric pressure, recovering from said overhead fraction a residual fraction containing substantial amounts of iso C₅ hydrocarbons and a second overhead fraction, polymerizing said second overhead fraction, fractionating the products of said polymerization into a C₄ fraction, an intermediate fraction including C₅ hydrocarbons, and a C₆ and higher fraction, hydrogenating the said intermediate fraction in admixture with the recovered iso C₅ hydrocarbons to saturate the compounds therein with hydrogen and produce an aviation fuel of good boiling range, blending said fraction containing the rest of the heavy naphtha, said bottom light naphtha fraction, said C₆ and higher fraction and enough of said C₄ fraction from the polymerization step to produce a balanced motor fuel of high sensitivity throughout its boiling range.
2. The process of claim 1 further characterized in that the polymerization is carried out at a temperature in the range of about 300° F. to about 400° F. and in the presence of a solid selective polymerization catalyst.
